INDUCTANCE COIL

Mendel Osnos, Berlin, Germany, assignor to Tele-funkens Gesellschaft fur Drahtlose Telegraphie m. b. H., Berlin, Germany, a corporation of Germany

Application August 2, 1933, Serial No. 683,240
In Germany August 15, 1932

6 Claims. (Cl. 175—359)

This invention relates to an inductance coil with variable or regulable or partly or wholly eliminable temperature dependency.

The invention consists in that the inductance coil is externally bounded by another body or a combination of bodies in such a fashion that in the presence of temperature fluctuations the diameter of the coil is able to change only in accordance with the temperature coefficient of expansion of the boundary body or combination of bodies, in other words, independently of the thermal expansion coefficient of the coil material, the axial length of the inductance coil, however, varying as a function of the last-mentioned coefficient.

This invention will be more clearly understood by referring to the accompanying drawing in which,

Fig. 1 shows a sectional view of an improved inductance coil;

Fig. 2 shows a sectional view of another modification of an improved inductance coil.

Referring now to Fig. 1, 1 denotes a cylinder made from material such as quartz whose coefficient of expansion is very low (for example, 1/30th that of copper), while 2 denotes a markedly elastic copper spiral, the outside diameter of which is reducible by the turning of the coil.

In free or normal state, the outside diameter of the coil is somewhat greater than the inside diameter of the quartz cylinder. Twisting the coil somewhat together it will be possible to force-fit it into the cylinder so that it will firmly be pressed upon and engage with the internal shell wall of the cylinder. Hence, the outside diameter of the spiral is always governed by the inside diameter of the quartz cylinder. The axial length of the spiral, however, is capable of unrestrained adjustment according to the temperature.

If the ratio between diameter D of the spiral and the circumference 0 of its winding is between 1 and 3, then the inductance thereof will be approximately

$$L = 10.5 \cdot N^2 \cdot D \cdot \sqrt{\frac{D}{U}} \text{ cm} \quad (1)$$

See Rein-Wirtz Radiotelegraphisches Praktikum, 1921, third edition, page 128, (where N equals the total number of turns, D equals the average diameter, $U = 2\pi(l+b)$, if l and b are respectively the length and thickness of the coil in centimeters). And since

$$D = D_0(l + \alpha_1 t) \quad (2)$$

$$U = U_0(l + \alpha_2 t)$$

where α_1 is the heat expansion coefficient of quartz, and α_2 the heat expansion coefficient of copper, while D_0 and U_0 , respectively are the values of D and U for $t=0$ degrees C., then we may write also

$$L = L_0 \sqrt{\frac{l + 3\alpha_1 t}{l + \alpha_2 t}} \quad (3)$$

where L_0 the value of the inductance at $t=0$, or else, since α_2 is very small compared with unity

$$L = L_0 \sqrt{\frac{l + 3\alpha_1 t}{l + \alpha_2 t}} \quad (4)$$

Putting

$$\alpha_1 = 1/30 \cdot \alpha_2,$$

then

$$L = L_0 \sqrt{\frac{l + 0.1\alpha_2 t}{l + \alpha_2 t}} \quad (5)$$

hence

$$L < L_0$$

Now, according to another object of this invention as shown by Fig. 2, if the inductance is to be made adjustable or regulable, then all or any desired part of the coil may be forced into the quartz cylinder. By the shifting of the cylinder it is then feasible to regulate ad libitum the dependence of the inductance coil upon the temperature.

If glass is employed as the cylinder material instead of quartz, then the effect of the cylinder will be lower in proportion to the lower expansion coefficient of glass.

In some instances it may be desirable to artificially increase the dependence of quantity L upon the temperature, for instance, when the inductance connected in parallel to a capacity determines the wave of a transmitter, and if the condenser is built so that its size decreases very markedly with the temperature. In this case the preferable plan will be to make the cylinder of a kind of material whose coefficient of expansion is greater than that of copper, say, ebonite.

I claim:

1. An inductance coil comprising a quartz cylinder, a metallic spiral coil having an outside diameter slightly greater than the inside diameter of said quartz cylinder, said spiral coil engaging the internal wall of said quartz cylinder so as to firmly retain said coil within said cylinder.

2. An inductance coil comprising a quartz cylinder, a metallic spiral inductance coil engaging the internal wall of said quartz cylinder so as to firmly retain said coil within said cylinder.
3. An inductance coil comprising a quartz cylinder, a spiral inductance coil whose axial length of spiral is capable of unrestrained adjustment according to the temperature, said inductance coil being retained within said quartz cylinder.
4. An inductance coil comprising a quartz cylinder having at least one of its ends flared out to a slightly larger diameter, a metallic spiral coil having an outside diameter slightly greater than the inside diameter of said quartz cylinder so as to firmly retain said coil within said cylinder.
5. An inductance coil comprising a quartz cylinder, a copper spiral coil having an outside diameter slightly greater than the inside diameter of said quartz cylinder, said copper spiral coil engaging the inner wall of said quartz cylinder so as to firmly retain said coil within said cylinder.
6. An inductance coil comprising a quartz cylinder having at least one of its ends flared out to a slightly larger diameter, a metallic inductance coil having an outside diameter slightly greater than the inside diameter of said quartz cylinder so as to firmly retain said coil within said cylinder, said inductance coil being movable within said cylinder.
